UNITED STATES PATENT OFFICE.

RICHARD CANE, OF LONDON, ENGLAND.

BEDSTEAD.

SPECIFICATION forming part of Letters Patent No. 729,842, dated June 2, 1903.

Application filed September 8, 1902. Serial No. 122,459. (No model.)

To all whom it may concern:

Be it known that I, RICHARD CANE, a subject of the King of Great Britain, and a resident of No. 2 Bridge road, South Hampstead, 5 London, England, have invented certain new and useful Improvements in Bedsteads, of which the following is a specification.

In the accompanying drawings, Figure 1 is an elevation of part of a round post or pillar 10 with the invention partly adapted thereto. Fig. 2 is a plan view of the pillar and socket. Figs. 3 and 4 represent in plan view two angle-bars of the frame adapted according to this invention. Fig. 5 is an edge view of one 15 of the bars. Fig. 6 is an elevation showing a square post with the angle-bars in position, (one bar being in section,) and Fig. 7 is a plan view of the same.

In the construction of bedsteads about to 20 be described various objects have been kept in view. For instance, provision should be made for adjusting the height of the frame from the floor according to requirements; next, the slipping of the spring-mattress off 25 the frame should be prevented; then a complete rigidity of the frame is necessary, and, lastly, simple means should be provided whereby the bedstead may be shifted about the room.

30 The bedstead may be either of metal or wood, and the pillars or posts may be either round, square, or other section.

A is the post or pillar of the bedstead, which 35 is provided with a series of holes B on what will be the inner side thereof.

C is a socket to receive the angle-bars, which socket may be shaped for a round post to partially embrace the post, and it is formed with lugs D, by which it is secured to the post

40 by screw-bolts E. These bolts E pass through the holes B and screw into a supporting-plate F on the inside of the pillar. The upper end of this plate F is shown in Figs. 2 and 7, and its edge is shown in dotted outline in Figs. 1 and 6. It may be inserted into the pillar from 45 the upper or lower end thereof and may extend any portion of the height of the pillar.

In the case of the square pillars, whether 50 metal or wood, the socket C may be provided with a threaded pin E*, cast with it or tapped into it, as indicated at Fig. 6, instead of a

second lug. This pin will screw into the post, and the socket will be secured by a lug and bolt, as before mentioned.

The socket C is formed with a rectangular 55 recess, in which studs or projections G are provided, (see Figs. 2 and 7,) and on the under side is a pivot-hole H for the end of the caster-pin, as will be presently explained.

I represents the side and end bars, known 60 as "angle-iron" frame-bars, which are of the usual L shape in cross-section, and they are set with the vertical side upward and outward, so as to form a recessed frame, in which the mattress is placed. These angle-bars, 65 the ends of which are mitered off, as shown in Figs. 3 and 7, are formed with holes J to fit onto the studs G of the socket. (See Figs. 6 and 7.)

The angle-bars I are held down in the sockets C by the triangular pieces K, which are 70 also formed with holes to fit onto the studs G. A piece K may be permanently bolted or otherwise secured to one bar end, (see Figs. 3, 4, 5, and 7,) and each piece K is provided with 75 bolts L, one of which will pass through the socket C, and notches formed in the mitered ends, and the other bolt will pass through the other bar, both being secured by fly-nuts M. (See Fig. 6.)

In place of fitting the pillars or posts with 80 casters of the usual character I prefer to employ an independent and larger caster or wheel N, mounted in a swivel-frame N*, as shown in Fig. 1. For this purpose I cast with 85 or otherwise secure to the pillar A a stay or bracket O to receive the pin P of the caster, which pin extends upward to the socket C, where it enters the pivot-hole H, before referred to.

Generally speaking, I intend to dispense with the laths and stretchers, which are unnecessary when box and similar mattresses are used; but the buttons for the laths may be provided on the bars I, if desired.

90 What I claim as my invention, and desire to secure by Letters Patent, is—

95 1. A bedstead comprising posts adapted to receive adjustable sockets and provided near the ends with brackets for casters, sockets 100 for the frame having a rectangular recess, studs on the bottom of the sockets and a pivot-

hole for the caster-pin, means for adjustably attaching the sockets to the posts, casters, including a large wheel in swivel-frame and a long pin extending from the caster-bracket 5 to the frame-socket, a frame composed of L-shaped or angle bars with vertical side upward and outward and having mitered ends and holes to fit on studs of sockets, triangular plates overlying the abutting ends of the 10 bars and bolts and fly-nuts for securing the parts together, all combined and operating as herein shown and described.

2. A bedstead furnished with sockets attached to the posts, recesses in said sockets, 15 studs within said recesses, a frame with slots at the corners fitting onto said studs in the recesses, and means for clamping said frame in position in the sockets.

3. In a bedstead, posts, with frame-sockets 20 having a rectangular recess and studs in its bottom; angle-bars with mitered ends and holes to fit the studs, triangular retaining- plates for the abutting ends of the bars and

bolts and fly-nuts, all combined as herein shown and described. 25

4. A bedstead comprising posts, sockets adjustable thereon, projections carried by said sockets, slotted detachable bars engaging with said projections to form a frame, and clamping means for co-operating with said 30 sockets to hold the so-formed frame rigidly in position, substantially as described.

5. In a bedstead, the combination with posts and a recessed frame, of sockets attached to the posts and having rectangular 35 recesses for the reception of said frame and having studs projecting upward from the bottoms of said recesses and entering holes in said frame, substantially as herein described.

In testimony whereof I have signed my 40 name to this specification in the presence of two subscribing witnesses.

RICHARD CANE.
